ICE TRAY

Uncas A. Whitaker, Canton, Ohio, assignor to
 The Hoover Company, North Canton, Ohio, a
 corporation of Ohio

Application September 12, 1938, Serial No. 229,414

13 Claims. (Cl. 62—108.5)

This invention relates to refrigeration, and more particularly to an ice tray adapted to be positioned in the freezing compartment of a domestic refrigerator.

The usual procedure in removing ice cubes from a freezing tray of a domestic refrigerator is to remove the tray having frozen cubes of ice therein from the freezing compartment and placing in a warm place until the cubes have melted loose or to pour hot water over the bottom of the tray until the grid assembly and attached cubes have melted loose from the tray; then remove the grid assembly and attached cubes from the tray and run more hot water over the attached cubes and grid assembly to melt the cubes loose from the grid assembly. The first procedure necessitates the removal of the tray with the frozen cubes from the freezing compartment long before the cubes will be needed so as to allow time for the cubes to melt loose. Both of these methods also result in the wastage of ice since in melting loose the cubes become reduced in size. The melting water on the surface of the cubes also make them slippery and hard to handle and the melting water messes up the kitchen unless special precautions are taken.

It has also been proposed to remove the grid assembly and attached cubes from the tray by means of a mechanical leverage mechanism and then to remove the attached cubes from the grid assembly by hand or by some other leverage mechanism.

These devices have not been entirely satisfactory due to the fact that it requires the application of a considerable amount of force to remove the grid assembly and attached cubes from the tray and also to remove the cubes from the grid assembly. These prior art devices are also complicated and expensive to manufacture and wear out easily thus necessitating periodical replacement.

Prior devices also have the disadvantage that the releasing mechanism is associated with the comparatively small grid assembly which necessitates the removal of the releasing mechanism along with the grid assembly and also results in a very complex grid assembly structure.

It is accordingly an object of this invention to provide an ice tray in which the releasing mechanism for the grid assembly and attached cubes is permanently associated with the tray itself.

It is another object of this invention to provide an ice tray in which only a small force need be applied to remove the grid assembly and attached cubes from the tray.

More particularly, it is an object of this invention to provide an ice tray having a flexible partition therein dividing the tray into an upper open compartment and a lower sealed compartment containing a fluid to which pressure may be applied so as to flex the partition upwardly and release ice from the upper compartment.

It is another object of this invention to provide an improved process whereby ice cubes may be easily removed from an ice tray.

It is another object of this invention to provide an ice tray which is simple in operation and easy and economical to manufacture.

Other objects and advantages of this invention will become apparent as the description proceeds when taken in connection with the accompanying drawing, in which:

Figure 1 is a longitudinal vertical section of one embodiment of the invention;

Figure 2 is a cross-sectional view on line 2—2 of Figure 1;

Figure 3 is a perspective view of another embodiment of the invention partly broken away to show the operating mechanism for applying pressure to the fluid beneath the partition.

Referring to Figures 1 and 2 of the drawing, the numeral 10 indicates an ice tray having side walls 11, end walls 12 and bottom 13. The side walls 11 and the end walls 12 are extended upwardly and outwardly to form a flange 14 extending entirely around the tray. A thin metallic partition 15, such as spring steel, having an upwardly extending flange 16 is welded to the interior of the tray so as to divide it into an upper, open ice receiving compartment and a lower sealed compartment. A piston chamber 17 having a tube 18 communicating with the interior of the lower sealed compartment is secured to the front of the tray by means of bracket 19 welded to the front of the tray.

A piston 20 having an operating handle 21 is mounted to reciprocate in the chamber 17 by means of a cover member 22 for the chamber having an opening therein to slidably receive the piston rod 23. An aperture 24 is provided in the cover member 22 so that a vacuum will not be produced when the piston is operated. With the piston in upper position as shown in Figure 1, the chamber 17 and the lower sealed compartment of the tray is filled with any non-freezing liquid 25 such as glycerine.

Removably positioned into the upper ice forming compartment of the tray is a grid assembly generally indicated at 26 made up of a central longitudinal grid member 27 of rubber or other

suitable flexible and moldable material. Imbedded in the central longitudinal grid member 27 are lateral grid members 28 which together with the central longitudinal grid members divide the upper ice freezing compartment of the tray into a plurality of cube compartments. The lateral grid members 28 are staggered as shown to give great lateral flexibility to the grid assembly. The lateral grid members 28 need not be staggered as shown but could be positioned directly opposite each other, with the parts extending on opposite sides of the central longitudinal grid members made integral and provided with openings at their center so that they could be molded into the rubber of the central longitudinal grid member.

The grid assembly need not be made of metal and rubber as shown but could be made entirely of rubber or any other suitable material.

20 As shown in Figure 2, the bottom 13 of the tray is corrugated so as to make it comparatively rigid. The corrugation need not be made as shown but could easily extend laterally across the bottom of the tray or the bottom of the tray could be reinforced in some other manner.

The chamber 17, bracket member 19, piston rod 23 and handle 21 may be used as a hand grip for handling the tray when removing and replacing it in the freeze chamber of a refrigerator so that no additional handle is necessary.

With the piston 20 in the position shown in Figure 1, the upper ice freezing compartment of the tray is filled with water to be frozen and the tray is then positioned in the freezing compartment of a domestic refrigerator and left there until the water has become frozen. The tray is then removed from the freezing compartment in any suitable manner and pressure is applied to the handle 21 forcing the piston 20 downwardly in the chamber 17, causing the fluid 25 to be forced into the lower sealed compartment of the tray which will cause the flexible partition member 15 to bulge upwardly releasing the grid assembly and attached cubes from the walls of the tray as shown in Figure 2. The grid assembly 26 and the attached cubes can then be easily raised from the tray and flexed laterally so as to remove the individual cubes from the grid assembly.

Due to the fact that the diameter of piston 20 is 50 comparatively small in area with relation to the flexible diaphragm 15, only a small amount of pressure need be applied to the handle 21 to release the grid assembly and attached cubes from the tray. The bottom 13 of the tray being corrugated or otherwise reinforced will not flex downwardly thus assuring that the flexible partition will be bulged upwardly. The flexible partition member 15 is made so as to normally maintain the position shown in full lines of Figure 2, and 55 when bulged upwardly to the position shown in dotted lines of Figure 2 it will snap backwardly to the full line position when pressure on the piston is released. If desired, any convenient form of biasing means may be located in the lower compartment to insure the return of diaphragm 15 to 60 its unbulged position.

The longitudinal corrugations in bottom 13 enable the lateral width of the tray to be shortened when pressure is applied to the piston to allow 70 greater flexing of diaphragm 15. If necessary, flange 16 of member 15 can be attached to the tray walls only at its upper edge so as to permit of greater flexibility by permitting the lower portion to draw away from the tray walls when the central portion of the diaphragm is flexed upwardly.

Due to the fact that the flexible partition member 15 bulges upwardly at the central longitudinal grid member, the outer edges of the cubes will be released from the flexible partition 15 first, so that a tearing stress is applied to the bond between the flexible partition member and the cubes. At the same time, the whole grid assembly and the attached cubes are raised upwardly so as to apply a shearing stress on the bond between the walls 11 and 12 and the cubes.

When the grid assembly and attached cubes are removed from the tray and flexed laterally, the outer ends of the lateral grid members will be separated so as to apply a tearing stress on the bond between the cubes and the lateral grid members 28 and at the same time, the central longitudinal grid member 27 will be flexed so as to be separated from the cubes by a tearing action.

The modification shown in Figure 3 is the same as that just described except for the operating mechanism for applying pressure to the fluid in the lower sealed compartment. The front wall 12 of the tray is extended outwardly and downwardly to form a housing 42 for a fluid reservoir 29. The bottom 30 of the reservoir 29 is extended downwardly and hollowed out to form a cylinder 31 to slidably receive a piston 32 having a piston rod 33 extending through the closure 34 of the cylinder. A lever 35 is pivoted to an extension of the cylinder walls and is connected by a loose connection to the piston rod 33 so that a pivotal movement of the lever 35 will reciprocate the piston 32 in the cylinder 31. A spring 36 coiled about the pivot pin for the lever 35 holds the piston 32 in its lowermost position. The cylinder 31 communicates with the bottom sealed compartment of the tray by means of a duct 37 having an outwardly opening check valve 38. The top of the reservoir 29 is made of flexible material such as rubber and the reservoir communicates with the interior of the cylinder 31 by means of an aperture 39 normally closed by means of a spring pressed check valve 40. The reservoir 29 also communicates with the duct 37 by means of a minute aperture 41.

When it is desired to remove the ice from the freezing compartment of the tray, the lever 35 is pressed downwardly which forces the piston upwardly, opening check valve 38 and forcing the fluid in the cylinder 31 through the duct 37 into the sealed compartment in the bottom of the tray, flexing the partition upwardly and releasing the grid assembly and attached cubes as described in connection with the modification of Figures 1 and 2. When the lever 35 is released, the spring 36 will force it upwardly and consequently the piston downwardly to the bottom of the cylinder 31 drawing liquid into the cylinder from the reservoir 29 through the aperture 39 by forcing the check valve 40 to open against the action of the spring. This causes the flexible portion of the reservoir 29 to bulge inwardly but since the flexible partition member 15 and the flexible portion of the reservoir 29 both have a natural tendency to return to their normal positions, the excess fluid in the sealed compartment in the bottom of the tray will slowly flow back to the reservoir 29 through the minute aperture 41. If one stroke of the piston is not sufficient to release the ice from the tray, the lever can be operated repeatedly until the ice is released. The remainder of the operation is the same as that described in connection with the modification of Figures 1 and 2.

The use of hydraulic means for releasing the ice from the tray eliminates to a great extent the

frictional forces present in prior cube release devices and thereby makes it unnecessary to apply so great a manual force in releasing the ice from the tray.

5 The piston and cylinder can be replaced by a siphon bellows pump if desired with leverage means for operating it. If one stroke is not sufficient to release the ice, inwardly and outwardly opening check valves could be provided with the bellows pump so that it could be operated repeatedly.

10 The piston and cylinder could be arranged horizontally so that the lever 35 could also be arranged horizontally and thus allow for a longer lever and therefore greater mechanical advantage.

15 From the foregoing, it can be seen that this invention has provided an ice tray in which the ice cubes can be easily removed by the application of only a small force and without the necessity of handling wet and slippery cubes, which is simple and efficient in operation and easy and economical to manufacture.

20 While I have illustrated and described but two embodiments of my invention, it is to be understood that these embodiments are to be taken as illustrative only and not in a limiting sense. I do not wish to be limited to the exact disclosure but to include all equivalent variations thereof except as limited by the scope of the claims.

25 I claim:

1. An ice cube tray having a resilient partition therein dividing said tray into an upper compartment and a lower sealed compartment, a fluid in said lower compartment and means for applying pressure to said fluid whereby the partition is flexed upwardly to release ice from said tray.

20 2. An ice tray for a domestic refrigerator having a flexible partition therein dividing said tray into an upper open compartment and a lower sealed compartment, a fluid in said lower compartment and means for applying pressure to said fluid whereby the partition is flexed upwardly to release ice from said tray, said pressure applying means being in the form of a fluid pump.

25 3. An ice cube tray having a resilient partition therein dividing said tray into an upper open compartment and a lower sealed compartment, a grid assembly in said upper compartment, said grid assembly comprising a resilient longitudinal grid member and rigid lateral grid members secured thereto, a fluid in said bottom compartment and means whereby a pressure may be applied to said fluid to flex the partition upwardly to remove said grid assembly and attached cubes from the tray.

40 4. An ice cube tray, flexible means dividing said tray into upper and lower compartments, a fluid in said lower compartment, a handle for said tray and means associated with said handle for applying pressure to said fluid.

45 5. An ice cube tray, a grid assembly removably positioned therein, said grid assembly comprising a resilient longitudinal grid member and

rigid lateral grid members, said lateral grid members on opposite sides of said longitudinal grid member being secured in staggered relation to said longitudinal grid member and means beneath said grid assembly for ejecting cubes from 5 said tray.

6. An ice cube tray, a grid assembly removably positioned therein, said grid assembly comprising a resilient longitudinal grid member and rigid lateral grid members, said lateral grid members being secured in staggered relation to said longitudinal grid member and means beneath said grid assembly for ejecting cubes from said tray, said cube ejecting means being sealed from 10 said grid assembly.

15 7. An ice cube tray, a resilient partition dividing said tray into an upper open compartment and a lower compartment, a grid assembly removably positioned in said upper compartment and means in said lower compartment to flex 20 said partition upwardly to release said grid assembly and attached cubes from said tray, said grid assembly being so constructed as to be flexed laterally to release individual cubes from said grid assembly.

25 8. An ice cube tray, an elastic partition dividing said tray into an upper open compartment and a lower compartment, a grid assembly removably positioned in said upper compartment and means in said lower compartment to flex 30 said partition upwardly to release said grid assembly and attached cubes from said tray, said grid assembly being so constructed as to be capable of being flexed laterally to remove individual cubes from said grid assembly and said flexing means comprising a fluid motor.

9. An ice cube tray, a flexible partition dividing said tray into upper and lower compartments, said tray having a reinforced bottom and a fluid filling the space between the partition and the bottom.

10. An ice cube tray, a flexible partition dividing said tray into upper and lower compartments, said tray having a corrugated bottom, a fluid filling the space between the partition and bottom and means for applying pressure to said fluid.

11. An ice tray, resilient means sealing off a portion of said tray, cube releasing means beneath said resilient sealing means, and manually actuatable means for transmitting force to said cube releasing means.

12. In combination, an ice tray having an ice compartment, manually actuatable force transmitting means beneath said compartment for breaking the bond between the ice and tray and flexible sealing means between said compartment and said force transmitting means.

13. An ice cube tray, flexible means sealing off a portion of said tray, cube releasing means between said flexible sealing means and the tray, and means for transmitting force to said cube releasing means, said cube releasing means comprising hydraulic means.

UNCAS A. WHITAKER.
